Inventor

K. FRAZER

United States Patent Office.

KASSON FRAZER, OF SYRACUSE, NEW YORK.

Letters Patent No. 69,087, dated September 24, 1867.

IMPROVED SNAP-HOOK.

The Schedule referred to in these Letters Patent and making part of the same.

TO ALL WHOM IT MAY CONCERN:

Be it known that I, KASSON FRAZER, of the city of Syracuse, New York, have invented a new and improved Snap; and I do hereby declare that the following is a full, clear, and exact description of the construction of the same, and the form thereof when complete, reference being had to the annexed drawings, making a part of this specification, in which—

Figure 1 represents a face view of the hook part.

Figure 2 represents a side and sectional view thereof.

Figure 3 represents a face view of the latch part.

Figure 4 a side and sectional view, and

Figure 5 a back view thereof.

Figure 6 represents a side view of the whole snap complete.

The letters used represent the same parts in the different figures where they appear.

To enable others skilled in the art to make and use my invention, I will proceed to describe the construction of the snap, and its form when complete and ready for use.

I make of malleable iron or other metal a hook, with a ring part, A, and a hook part, B, substantially in the form represented by figs. 1 and 2, and with a bevelled face, *a*, at the end of the hook, as seen in figs. 2 and 6. I make a latch, C, of the same metal, substantially in the form seen in figs. 3, 4, and 5, with a bevelled face, *b*, to fit the face *a* on the hook B, when the snap is closed, and with the small hooks *c c* to fit and bear against the ring part of the hook, as seen at the points *d d*. I also make a steel spring, D, with one end thereof inserted in the latch C, as seen at *e*, in figs. 4 and 5, and with the other end flattened, and the body thereof made in the form of a spring, so as to bear upon the hook part at the point *f*.

The spring is thus made to answer the double purpose, first, of an ordinary spring, in opening and closing the latch; second, in combination with the small hooks *c c*, the bevelled faces *a* and *b*, and the bearings at *e* and *f*, holding the hook part and the latch together, thus avoiding the necessity of drilling, riveting, or clinching, to secure and hold the latch to the hook.

What I claim as my invention, and desire to secure by Letters Patent, is—

The constructing of a snap by a combination of the parts A, B, C, and D, or their equivalents, substantially as and for the purpose described.

KASSON FRAZER.
